UNITED STATES PATENT OFFICE.

CARL RASMUSSEN, OF BRUNSWICK, GERMANY.

CALCULATING-MACHINE.

1,150,705.

Specification of Letters Patent. Patented Aug. 17, 1915.

Application filed November 27, 1914. Serial No. 874,326.

To all whom it may concern:

Be it known that I, CARL RASMUSSEN, engineer, a subject of the King of Norway, residing at Brunswick, Germany, have invented 5 certain new and useful Improvements in Calculating-Machines, of which the following is a specification.

My invention relates to improvements in calculating machines, and more particularly 10 in calculating machines of the class in which the carrying mechanism consists of rockers coöoperating one with each of the numeral wheels of the registering mechanism (except the one of the highest order), which 15 rockers are adapted to set the mechanisms for transmitting the values to the numeral wheels of the higher orders in such a way that the said numeral wheels are shifted a distance corresponding to one value, which 20 rockers are operated by the numeral wheels when passing from the "nine" position to the "zero" position, or vice versa. The object of the improvements is to provide novel locking means for holding the said rockers 25 in operative positions until the carrying operation has been completed, which locking means are simultaneously thrown in non-locking positions by the mechanism for transmitting the values to the numeral 30 wheels.

For the purpose of explaining the invention I shall describe hereinafter a calculating machine of the class in which setting disks are provided for setting and transmitting the values to the numeral wheels of the registering mechanism upon rotation by a machine crank. A machine of this class is shown and described in the Patent of the United States No. 1,100,689 granted to me 35 on June 16, 1914. But I wish it to be understood, that my invention is not limited to the embodiment in a machine of the type shown in the said patent.

In the drawing Figure 1, is a vertical 40 cross-section of the registering and carrying mechanism of the calculating machine. Fig. 2, is a partial plan view of the machine with the cover of the casing removed, and Fig. 3, is a side view showing a detail of 45 the machine illustrated in Figs. 1 and 2.

Referring to the example illustrated in the drawing, the registering mechanism comprises intermediate gear wheels n adapted to be operated from the setting mechanism upon rotation thereof by the machine 50 crank. As the setting mechanism does not

form a part of my invention I have not illustrated the same in the figures. In the operation of the machine the intermediate gear wheels are rotated through arcs which correspond to the numbers set on the setting disks, and such rotation is transmitted from the intermediate gear wheels to coöperating numeral wheels k through the intermediary of gear wheels k^2 connected one with each 55 of the numeral wheels.

The numeral wheels k or the gear wheels k^2 are each provided with a nose k^1 which is adapted to rock a member h having a rocking support on a relatively fixed shaft i , 70 and the noses k^1 are disposed in such positions, that the rocking movement is imparted to the members h whenever the numeral wheels pass from their "nine" positions to their "zero" positions, or vice versa. An 75 arm h^1 of the rocker carries a block g which is formed with two cam faces arranged on opposite sides of the block. The block g is located at the side of a disk f which is provided with a radially shiftable tooth e 80 (or where the setting mechanism is adapted to be rotated in both directions with two teeth one for multiplication and the other one for division). The tooth e is located in such a position that when shifted into operative position it engages in the teeth of the intermediate gear wheel n of the next higher order. For shifting the tooth it is formed with a lateral nose e^1 which is located in the path of the block g and adapted to ride on 85 the cam face thereof. The disk f is operatively connected with the machine crank or a part connected therewith, so that it takes part in the rotation of the same and the setting mechanism, and when it is rotated with 90 the tooth e in operative position the intermediate gear wheel n of the next higher order is rotated through an angle corresponding 95 to one value.

The rocker h , h^1 must be held in operative 100 position, until the tooth e has passed and performed the carrying operation. For this purpose it is provided with an arm h^2 which is adapted to be engaged by a spring d when the rocker h is rocked, so that the latter can 105 not return into normal or inoperative position.

In order that all the rockers h , h^1 can simultaneously be returned into operative positions, the springs d are secured to a rock 110 shaft m which is held by a spring b with the springs d in locking positions, and which is

adapted to be rocked with the springs *d* away from the rockers *h*, *h*¹, so that all the rockers are released and drop into their normal or inoperative positions shown in Fig. 1. 5 Automatic means are provided for rocking the shaft *m* with the springs *d* out of locking engagement with the rockers *h*. As shown the shaft *c* is provided with a cam *a* which is adapted to engage a lever *m*¹ secured to the shaft *m* so as to rock the latter with the springs *d* out of locking engagement with the rockers *h*, *h*¹. 10

I claim herein as my invention:

15 In a calculating machine, the combination with the numeral wheels, and mechanism for transmitting values thereto, of rockers located in positions for being rocked by said

numeral wheels, means controlled by said rockers for carrying a value to the numeral wheels of higher order, spring locks one for 20 each of the rockers and adapted to lock the rockers in rocked positions, a rock shaft carrying all of said spring locks, and means controlled by said transmitting mechanism for rocking said rock shaft with the spring 25 locks out of locking positions.

In testimony whereof I have hereunto set my hand in presence of two subscribing witnesses.

CARL RASMUSSEN.
